land, assignors to Dunlop Tire and Rubber Cor-
poration, Buffalo, N. Y., a corporation of New
York

Application April 7, 1937, Serial No. 68,608
In Great Britain December 7, 1936

Term of patent 14 years

To all whom it may concern:

Be it known that we, Frank George William King and Leonard John Lambourn, subjects of the King of Great Britain and residents of "Guy Harlings", Wyvern Road, Sutton Coldfield, county of Warwick, England, and Erdington, county of Warwick, England, respectively, have invented a new, original, and ornamental Design for a Tire, of which the following is a

specification, reference being had to the accompanying drawing, forming a part thereof.

Fig. 1 is a perspective view; and Fig. 2 is a plan view of a section of a tire showing our new design.

We claim:—

The ornamental design for a tire as shown.
